CERTAIN PYRIMIDO(4,5-b)INDOLES AND
INTERMEDIATES EMPLOYED IN THEIR
PREPARATION

ABSTRACT OF THE DISCLOSURE

The compounds are of the class of 3-amido-3,4-dihydro-4-oxo-pyrimido[4,5-b]indoles which may be substituted at the 2-position by a linear alkyl group having from 1 to 3 carbon atoms, and may also be substituted at the 5-, 6-, 7- or 8-position by chloro or methoxy, e.g., 3-formamido-3,4-dihydro-4-oxo-pyrimido[4,5-b]indole. The compounds are obtainable by reacting an appropriate 2-aminoindolo-3-carboxylic acid lower linear alkyl ester with hydrazine to form the corresponding hydrazide which is then reacted with a linear fatty acid having from 1 to 4 carbon atoms. The compounds are useful as antihypertensives and diuretics.

This invention relates to pyrimido[4,5-b]indoles, and more particularly to 3-amido-3,4-dihydro-4-oxo-pyrimido[4,5-b]indoles and salts thereof and a process for the preparation thereof. The invention also relates to intermediates in the preparation of said compounds and a process for preparation of said intermediates. The 3-amido-3,4-dihydro-4-oxo-pyrimido[4,5-b]indoles of this invention may be represented structurally as follows:

wherein

R¹ is a member selected from the group consisting of a hydrogen atom, chloro and methoxy; and
R² is a member selected from the group consisting of a hydrogen atom, and linear alkyl having from 1 to 3 atoms, i.e., methyl, ethyl and propyl.

Compounds I are obtained according to the procedure of the following reaction scheme wherein R¹ and R² are as defined above and R³ is lower linear alkyl, e.g., having from 1 to 6 carbon atoms:

According to the reaction scheme, Step a involves the

preparation of a Compound III, i.e., a hydrazide, from a Compound II, i.e., a 2-aminoindol-3-carboxylic acid lower linear alkyl ester, in a conventional manner. It is preferred to prepare the Compound III by heating a Compound II in a large excess of anhydrous hydrazine, e.g., 5 to 20 fold by weight, under reflux. If desired the reaction may be carried out in a suitable solvent, e.g., toluene, using from 1 to 2 molar equivalents of hydrazine and at 80° to 120°.

Step b is a cyclization of the Compound III to the corresponding Compound I, which is effected by heating at from 90° to boiling, preferably by refluxing, a Compound III in a large excess, e.g., 5 to 40 fold by weight, of a Compound IV, which is a lower linear fatty acid having from 1 to 4 carbon atoms, i.e., formic acid, acetic acid, propionic acid or butyric acid. If desired, the cyclization can be carried out in a suitable solvent, e.g., xylene, using from 2 to 4 equivalents of the Compound IV at temperatures of from 90° to the boiling point of the Compound IV.

Compounds II may be obtained according to the procedure described by C. A. Grob and O. Weissbach in "Helvetica Chimica Acta," volume 44, pages 1748 to 1753 (1961).

Compounds I are useful because they have pharmaceutical activity. They are useful as antihypertensives and diuretics. They are administered to mammals either orally or parenterally in daily doses of from 5 to 20 mg./kg. of body weight, e.g., for large mammals from 300 to 1200 milligrams per diem, preferably administered in doses of from 75 to 600 milligrams; a single daily oral dose is also acceptable.

For the above uses, the compounds may be combined with a pharmaceutically acceptable carrier, and such other conventional adjuvants, as may be necessary, and administered orally in such forms as tablets, capsules, elixirs, suspensions or solutions, or parenterally in such forms as injectable solutions, suspensions or emulsions. Furthermore, the compounds may be similarly administered in the form of their non-toxic pharmaceutically acceptable acid addition salts. Such salts possess the same order of activity as the free base, are readily prepared in conventional manner by reacting the base with the appropriate acid and accordingly are included within the scope of the invention. Representative of such salts are the mineral acid salts such as the hydrochloride, hydrobromide, sulfate, phosphate and the like and the organic acid salts such as the succinate, benzoate, acetate, maleate, p-toluenesulfonate, benzenesulfonate and the like.

For example, each of the pharmaceutically active compounds of this invention may be incorporated, for oral administration, in a tablet as the sole active ingredient. A typical tablet is constituted by from 1 to 3 percent binder, e.g., tragacanth; from 3 to 10 percent disintegrating agent, e.g., corn starch; from 2 to 10 percent lubricant, e.g., talcum; from 0.25 to 1.0 percent lubricant, e.g., magnesium stearate; and average dosage of active ingredient; and q.s. 100 percent of filler, e.g., lactose; all percentages being by weight. Tablets are prepared according to standard tabletting techniques, which are well-known in the art, employing the necessary amounts of conventional granulating liquids, e.g., alcohol SD-30 and purified water. An exemplary tabletting formulation for the instant active compounds is:

	Parts
Title compound of the example	75
Tragacanth	2
Lactose	14.5
Corn starch	5
Talcum	3
Magnesium stearate	0.5
Alcohol SD-30, purified water, q.s.	

The title compound of the example is also useful as an appetite suppressant.

An example illustrative of this invention follows. Throughout this disclosure all temperatures are centigrade (room temperature is 20°) and all percents and parts are by weight, unless specified otherwise. Parts by weight are related to parts by volume as a kilogram is related to a liter.

EXAMPLE

3-formamido-3,4-dihydro-4-oxo-pyrimido[4,5-b]indole

This example illustrates the preparation of a Compound I according to the reaction scheme presented above.

(a) 2-aminoindol-3-carboxylic acid hydrazide

Dissolve 10 parts of 2-aminoindole-3-carboxylic acid ethyl ester in 100 parts by volume of 95% anhydrous hydrazine and reflux the mixture for 20 hours. Cool the mixture and evaporate under vacuum to obtain a residue. Dissolve the residue in methanol and remove the residual hydrazine by evaporating under vacuum. Crystallize the residue from ethanol to obtain crude Compound *a*, then recrystallize from ethanol-chloroform (2:1) to obtain purified Compound *a*, melting point (M.P.) 201° to 205°.

(b) 3-formamido-3,4-dihydro-4-oxo-pyrimido-[4,5-b]indole

Reflux a mixture of 10.4 parts of purified Compound *a* and 200 parts by volume of 98 to 100% formic acid for 15 hours. Dilute the reaction mixture with 400 parts by volume of water, to form a precipitate of crude title compound, which then separate by filtration and wash on the filter first with 200 parts by volume of water then 50 parts by volume of ethanol and finally 100 parts by volume of diethyl ether. Recrystallize from 500 parts by volume of ethanol-dioxane (1:1) to obtain the purified title compound, M.P. 312° to 315°.

Following the procedure described in Step *a* of this example but replacing the 2-aminoindole-3-carboxylic acid ethyl ester with an equivalent amount of 4-chloro-2-

aminoindole-3-carboxylic acid butyl ester or 7-methoxy-2-aminoindole-3-carboxylic acid hexyl ester results, in a similar manner, in the preparation of the respective corresponding Compounds III, which by following the procedure of Step *b* of the example but replacing the formic acid with an equivalent amount of propionic acid results, in a similar manner, in the preparation of the respective corresponding Compounds I.

What is claimed is:

1. A compound which is a member selected from the group consisting of (A) a compound of the formula

wherein

R¹ is a member selected from the group consisting of a hydrogen atom, chloro and methoxy; and

R² is a member selected from the group consisting of a hydrogen atom, methyl, ethyl and propyl; and

(B) a pharmaceutically acceptable acid addition salt of a compound of said formula.

2. The compound according to claim 1 wherein each of R¹ and R² is a hydrogen atom.

3. A compound of the formula:

wherein

R¹ is a member selected from the group consisting of a hydrogen atom, chloro and methoxy.

4. The compound according to claim 3 wherein R¹ is a hydrogen atom.
